WASHCLOTH

Gerard A. Benedict, New York, N. Y.

Application June 7, 1933, Serial No. 674,612

6 Claims. (Cl. 15—208)

This invention relates to washing cloths and, more particularly, to dishcloths.

An object of the invention is to provide a washing cloth whereby soap in flake or similar form may be utilized in a particularly satisfactory and efficient manner.

More specifically, it is an object of the invention to provide a washing cloth which will effectively receive and hold soap flakes.

10 Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had 20 to the following detailed description taken in connection with the accompanying drawing, in which:

Figure 1 is a perspective view of a dishcloth embodying the invention, showing soap flakes 25 being introduced thereinto;

Fig. 2 is a top view of the cloth with soap flakes therein;

Fig. 3 is a top view of a slightly modified form of dishcloth; and

30 Fig. 4 is a plan view of another form of dishcloth embodying the invention.

For the sake of facility of expression, the term "soap flakes" is used herein to include soap flakes, soap granules, soap beads, soap powders, soap 35 shavings, etc.

In spite of the many advantages of soap flakes in dishwashing, the ordinary use of soap flakes is distinctly inefficient. Where the flakes are introduced directly into the dishwater, enough soap 40 must be used to bring the entire body of water up to the necessary soap content for cleaning the greasy dishes which necessarily requires a generous use of the flakes. Furthermore, there is also a tendency for certain of the flakes to stick 45 to the dishes so as to be exceedingly difficult to remove. With a view to effecting a saving in soap and of preventing contact of the soap flakes with the dishes, and also to rendering the actual dishwashing operations easier for the housewife, 50 the present invention contemplates the provision of a dishcloth having a pocket in which soap flakes may be introduced and retained during use.

An important feature of the invention is the 55 provision of a pocket of such nature that the

soap flakes may be introduced into the pocket with the utmost ease and will at the same time be effectively retained in the pocket during use of the cloth. With such a dish cloth, all that is necessary is to introduce a small quantity of soap flakes into the pocket by the hand or from one of the boxes in which such flakes are commonly sold on the market, to wet the cloth, and to rub the cloth on the dishes to be cleaned. The water contained in the cloth will have a high soap 10 content and a large quantity of soap will be applied directly to the dish without dissolving a large quantity of soap in the water contained in the dishpan, so that exceedingly economical and satisfactory results may be secured.

15 There are exemplified in the drawing several of the types of dishcloths which may be provided in accordance with the invention.

In Fig. 1, there is shown a dishcloth comprising layers 11 and 12 of fabric joined at their side and bottom edges and also joined along two spaced inner parallel lines by stitching 13 and 14. The layers are also united at their upper edges along the lines running outwardly from the stitching 13 and from the stitching 14 to their side edges 20 respectively, but are not united in the space between these lines. There is accordingly provided a pocket 15 readily adapted to contain soap flakes and having an opening 16 at the upper end through which soap flakes may be introduced. 25 As indicated, this opening is considerably larger than the average human hand size so that the hand of the user may readily be introduced to deposit the soap flakes in the pocket. An opening of this size, moreover, will permit one end 30 of the top of an ordinary commercial soap flake box to be introduced in the opening and the flakes shaken into the pocket, if desired. As will also be seen, the pocket is of sufficient depth to effectively retain the soap flakes deposited therein. 35 The flakes may be introduced into a wet cloth or into a dry cloth which is thereafter wet. The soap, as it dissolves, oozes thru the fabric onto the dish being cleaned. After the dishes have been washed, the cloth may be rinsed and hung up, since it is to a large extent self-washing. Accordingly, both the bother of scrubbing out the cloth and the temptation to hang it up dirty 40 are avoided.

45 The exemplified dishcloth may be formed if desired from tubular fabric, e. g., tubular knit fabric, with cut edges either parallel to the sides of the pocket or perpendicular thereto. As exemplified, these cut edges are parallel to the sides 50

of the pocket and are joined by lines of stitching indicated at 18 and 19. The fabric in this instance is slit at its upper ends between the lines 13 and 14 so as to provide the opening for the pocket, and the edges for this pocket are stitched as at 20 to prevent raveling. The fabric should be knit or woven sufficiently tightly to prevent the escape of the soap flakes to be used.

If desired, the cloth may be constructed so that 10 the upper ends of the spaces between the edges of the central pocket and the sides of the cloth may also be left open, so as to provide supplemental pockets 21 and 22 as indicated in Fig. 3.

In Fig. 4, there has been exemplified another 15 form of construction embodying the invention and comprising a layer of fabric 23 and a smaller layer of fabric 24 joined to the other along spaced lines 25 and 26, and along its bottom as at 21, but not joined at its top. There is thus provided a pocket 28 having an upper opening 29, which opening is substantially larger than the average human hand, so as to permit soap flakes to be readily deposited therein. Desirably, the piece 24 should be long enough to provide a pocket 25 of substantial depth, so that the soap flakes will be readily retained in it.

It will thus be seen that there is provided in accordance with the invention a dish cloth whereby soap flakes may be utilized efficiently and with 30 great ease and effectiveness for dish washing.

Since certain changes may be made in the above article and different embodiments of the invention could be made without departing from the scope thereof, it is intended that all matter contained in the above description or shown in the accompanying drawing shall be interpreted as 35 illustrative and not in a limiting sense.

It is also to be understood that the following 40 claims are intended to cover all of the generic and specific features of the invention herein described, and all statements of the scope of the invention which, as a matter of language, might be said to fall therebetween.

Having described my invention, what I claim 45 as new and desire to secure by Letters Patent, is:

1. A washing cloth comprising two layers of fabric joined along four spaced parallel lines including two inner lines well spaced from each other, and joined in a transverse direction along a continuous line adjacent one edge and lines extending from said inner lines outwardly at the other edge, said layers being entirely unconnected between said inner lines at said other edge.

2. A washing cloth comprising two layers of fabric joined along four spaced parallel lines including two inner lines well spaced from each other, and joined in a transverse direction along a continuous line adjacent one edge, said layers being unconnected at the other edge except where said parallel lines meet the edge. 5

3. A washing cloth comprising a tubular fabric united at its ends and along spaced lines parallel to and spaced from its ends, said fabric being slit 10 at one edge from one of said spaced lines to an adjacent one of said spaced lines.

4. A washing cloth comprising a sheet of fabric a portion of which is folded over along a transverse line upon at least a portion of the remainder of the sheet, said folded portion being stitched along four spaced lines extending in a direction generally perpendicular to said transverse line, the space between the two innermost lines being open at the edge remote from the fold to form 20 an open top and being closed at its sides and bottom to provide a pocket adapted to contain soap flakes, the outermost lines extending to said fold and the said two innermost lines extending in said perpendicular direction from said open top 25 to at least a point in proximity to said fold.

5. A washing cloth comprising a sheet of fabric, a portion of which is folded over along a transverse line upon at least a portion of the remainder of the sheet, said folded portion being 30 stitched along four spaced lines extending generally perpendicularly from the folded edge of the folded portion, the space between the two innermost lines being open at the edge remote from the fold to form an open top and being closed at its 35 sides and bottom to provide a pocket adapted to contain soap flakes.

6. A washing cloth comprising a single sheet of fabric doubled upon itself and joined by lines of stitching at its ends and by a pair of lines of 40 stitching spaced from its ends and extending generally parallel thereto and having an open portion therebetween at one end of said lines, said lines of stitching defining the sides of a pocket extending from said open portion between the 45 folds of the fabric to a point near the opposite folded edge of the fabric and adapted to retain soap flakes.

GERARD A. BENEDICT.
